UNITED STATES PATENT OFFICE.

EDWIN G. MUMMERY, OF DETROIT, MICHIGAN.

DESIGN FOR A WALL FOR HYDROCARBON-BURNERS.

SPECIFICATION forming part of Design No. 32,163, dated January 30, 1900.

Application filed January 2, 1900. Serial No. 171. Term of patent 14 years.

To all whom it may concern:

Be it known that I, EDWIN G. MUMMERY, a citizen of the United States, residing at Detroit, county of Wayne, State of Michigan, 5 have invented and produced a certain new and original Design for the Wall of a Hydrocarbon-Burner, of which the following is a specification, reference being had to the accompanying drawings, which form a part thereof.

- o In the drawings illustrating my design, Figure 1 is a view in perspective showing a wall of a hydrocarbon-burner embodying my design. Fig. 2 is a view in vertical section on the line 2 2, Fig. 1.
- 5 As shown in the drawings, the leading and material feature of my design consists of a tubular body (indicated at A) provided with a series of vertical ribs α , projecting outward

from the body of the wall. The upper end of the body of the wall is also provided with 20 an outwardly-projecting flange a' . The body of the wall is also formed with a series of horizontal annular kerfs or openings α^2 . The tubular body is open at its upper and lower extremities, as shown. 25

Having described my invention, what I claim as new, and desire to secure by Letters Patent, is—

The design for a wall of a hydrocarbon-burner herein shown and described. 30

In testimony whereof I sign this specification in the presence of two witnesses.

EDWIN G. MUMMERY.

Witnesses:
N. S. WRIGHT,
HELENA HILL.
